UNITED STATES PATENT OFFICE

LELAND K. BUTLER, OF MANCHESTER, NEW HAMPSHIRE, ASSIGNOR, BY MESNE ASSIGNMENTS, TO EXCEL TAPING MACHINE CO., OF LYNN, MASSACHUSETTS, A CORPORATION OF MASSACHUSETTS

MACHINE FOR APPLYING TAPE TO SHEET UNITS

Application filed April 5, 1928. Serial No. 267,715.

This invention relates to a machine for applying reinforcing tape to sheets of material, such as the uppers of shoes, and more particularly to the heel seams or back seams thereof, and in some aspects comprises an improvement upon and an adaptation of the apparatus disclosed in my copending application Serial No. 267,714, filed on even date herewith.

10 The machine provided by the present invention is particularly useful in applying adhesive reinforcing tape to a portion of an upper which has a substantially concavo-convex curvature with a seam located at its back. For example, certain types of uppers which are well known to the trade are formed by sewing two sheets of material, such as satin, with the body portions of the sheets substantially face to face at one side of the 15 curved seam and with narrow marginal portions lying face to face at the opposite side of the seam. The adjoining face portions of the sheet are then turned so that they are spaced from each other to define the outer 20 portion of the rear of the shoe, while the faces of the sheet which were originally outermost are turned inwardly and the narrow marginal portions which adjoin the seam are flattened back against the face portions and 25 held in place with the adhesive tape which also serves to reinforce this portion of the upper.

The present invention permits the upper to be turned preliminary to the application of 30 the tape to the seam so that the tape and seam are united while occupying the relative positions which they are to retain during actual use, the tape-applying means preferably being designed to operate continuously to press the tape smoothly upon the 35 same. Suitable guiding means are arranged in conjunction with the tape-applying means so that the upper is turned in order to permit the application of the tape in the position 40 which it will finally occupy when the upper portion is used in a shoe; for example, when a satin or similar sheet unit is to be reinforced, I provide guide means arranged to lie between the body portions of the sheet at a 45 point adjoining the seam and to spread these 50

portions so that they extend in opposite directions. At the same time I provide a pointed ridge element which separates the narrow marginal portions of the sheets and tends to spread them apart, directing them outwardly into substantial parallelism with the main portion of the respective sheets as the work passes between the juxtaposed tape-applying rolls. These rolls cooperate with the guide means in holding the upper properly turned so that the reinforcing seam is upon the inner or concave side of the same while the tape is being applied thereto. When leather uppers having similarly disposed back seams are to be reinforced with tape, similar guide means may be used in conjunction with a machine of this character or other suitable guide means may be used to perform an equivalent function.

In the accompanying drawings, which illustrate by way of example certain embodiments of the invention,

Fig. 1 is a front elevational view of a portion of the improved tape-applying machine;

Fig. 2 is an end elevation of a portion of the same;

Fig. 3 is a top view of a portion of the assembly shown in Fig. 2;

Fig. 4 is a detail sectional view showing one form of tape-applying rolls;

Fig. 5 is a view similar to Fig. 4 showing another type of rolls;

Fig. 6 is an elevational detail showing an optional form of guiding means;

Fig. 7 is a section on line 7—7 of Fig. 6;

Fig. 8 is an elevational view of the tape-applying means showing positions of the upper in relation to the same;

Fig. 9 is an elevational detail showing a modified form of guide particularly suitable for use with leather uppers;

Fig. 10 is a section on line 10—10 of Fig. 9; and

Fig. 11 is a plan view of a guide for sheet units, such as satin upper portions.

A machine of the type exemplified in the accompanying drawings preferably comprises a frame, designated in general by the numeral 1, which may be mounted upon any

55

60

65

70

75

80

85

90

95

100

suitable table or support. One end of frame 1 preferably supports a train of gears, designated in general by the numeral 2. This gear train is driven from any suitable source of power by a belt 3 passing over a pulley 4 which is provided with a weighted rim 5 that not only comprises a flywheel but also forms a hand wheel to permit manual movement of the parts in order to permit accurate adjustment of the machine for the insertion of new work or any other desired purpose. Mounted above frame 1 is a transverse shaft 7 which is rotated by the gear 8 which is loosely meshed with an adjoining gear 9 of the train 2. The shaft 7 is carried upon an upper roll support 12 which is pivotally connected to the frame 1 adjoining the gear train, as designated by numeral 13. The overhanging end of shaft 7 opposite the gear 8 carries a roll 10 for pressing the sheet material against the adhesive tape. The weight of the support 12 as well as any suitable spring, not shown, may serve to press the roll 10 downwardly toward a lower tape-applying roll 20 which is rotatably mounted upon the frame 1. Roll 20 is mounted upon a shaft 11 which extends through frame 1 and carries the gear 9 at its opposite end.

A depending box-like portion 15 of support 12 may interfit with the upstanding projection 16 upon frame 1 to serve as a guide for the support. It is evident that the loose meshing engagement of the gear 8 with the adjoining driving gear 9 cooperates with the pivotal mounting of support 12 to permit the rolls 10 and 20 to separate to allow the interposition of sheet material and tape therebetween.

A bracket 30 extends outwardly from frame 1 and supports a suitable axle 31 upon which a tape roll 32 may be located. Preferably this roll may be formed of tape that is coated with a permanently plastic adhesive which may be pressed into engagement with a sheet at ordinary temperature. The roll 32 preferably is surrounded by a suitable guard 35 comprising opposite plates 33 and 34. One of these plates, i. e. plate 34, is fixed to bracket 30 and preferably carries a roller 36 about which the tape run may be turned, this roll preferably being located in substantially the same horizontal plane as the axis of roll 20, Fig. 2, and the tape run extending therefrom about the lower portion of the latter roll so that it is wrapped about a considerable peripheral portion of the same to ensure a firm frictional engagement between this roll and the tape. Plate 34 carries a curved flange 37 surrounding a peripheral portion of the tape roll, Figs. 1 and 3. The removable plate 33 preferably is provided with a set screw 68 engaging axle 31 to permit the ready removal of plate 33 and the replacement of the tape roll when necessary.

Adjoining the juxtaposed portions of rolls

10 and 20, is a suitable guide member 40 which is carried by a support 41^a mounted for transverse adjustment in relation to frame 1. Member 40 is provided with an opening or slot 41 suitably dimensioned to receive the tape and to hold the same properly positioned in relation to the rolls. Member 40 also carries an upwardly extending sheet guiding portion which may be formed of sheet metal and which is designated by numeral 44. This sheet guiding means is provided with a central ridge 45 which terminates in an upwardly projecting point 46 and the height of which is gradually reduced as it approaches the juxtaposed portions of the rollers. At either side of the ridge 45 are grooves 47 which may be provided with openings 48 to permit the edges of the marginal portions of the sheet to be visible to the operator of the machine. Outwardly of grooves 45 are the curved sheet metal portions 48 which provide smooth rounded surfaces for engagement with the body portions of the sheets. It is evident that the grooves 47 and ridge 45 merge into a curved surface at the end 90 of the member 40 adjoining the outlet of slot 41. The edge of this curved surface of member 40 may be provided with a centrally disposed notch 49 aligned with ridge 45.

Mounted upon the roll support 12 is a bracket 50 having a central extension 51 which curves downwardly in juxtaposition to the periphery of roll 10, this member having a ridge-like face portion which is adapted to engage and spread the juxtaposed sheets. Member 50 also has a pair of depending portions 53 which curve downwardly and rearwardly at either side of roll 10, the elements 53 being designed to engage the sheet portions as they leave the tape-applying means. Preferably the periphery of roll 10 is slightly concave and the periphery of roll 20 is complementarily formed, i. e. slightly convex. The face of this roll may have a central groove 18 formed thereon, as shown in Figs. 1 and 5.

A suitable scraper 55 is secured to support 12 and curves downwardly and inwardly toward the roll 10 so that its edge is disposed close to the back of that roll. A suitable guard 65 is arranged about the front of roll 20 to prevent accidental engagement of foreign objects with the adhesive face of the tape wrapped therearound. This guard is normally held in position by a spring 66 having a curved portion engaging a nub 67 upon the guard, it being evident that a pull upon the guard will cause the nub to engage the curved spring end with a cam-like action to release the guard and to permit the same to swing down away from roll 20, thus facilitating the feeding of a new run of tape about the lower roll and into the slot 41.

In the operation of a machine of this char-

acter, the tape run is wrapped around the lower portion of roll 20 and fed through the slot 41 in member 40. The driving means is then started so that the roll 10 is driven 5 in the direction indicated by the curved arrow of Fig. 2. The sheet unit may then be engaged with guide members 40, the pointed end of this member projecting between the marginal portions of the sheets adjoining 10 the seam, these marginal portions passing into the grooves 47 at either side of the ridge and being spread as the ridge and grooves decrease in depth. The openings 48 permit 15 the marginal portions of the sheets to be visible to the operator so that she may hold the upper properly centered as it passes to the tape-applying rolls. The lower end of the ridge-like spreader 51 is adapted to engage 20 the body portions of the sheets to ensure the spreading of the same. It is thus evident that the marginal portions of the sheets and the body portions thereof are bent outwardly away from the seam substantially 25 into parallelism with each other as they pass between the rolls 10 and 20; thus the sheet unit assumes a concavo-convex curvature with the marginal portions upon the convex side.

Due to the curvatures of the faces of rolls 30 10 and 20 the unit is turned as it passes between the rolls so that it becomes concave upon the side to which the tape is being applied. Fig. 8 shows in full lines the position of the upper portion as it is engaged with the 35 guide means, and in the dotted line position shows the same as it is turned. The depending elements 53 engage the opposite sheet portions in order to retain the same in their turned position and to overcome any tendency 40 of the upper to spring back into its original shape. The guard 55 is arranged to prevent tape from clinging to the upper roll 10 and to continue to be wrapped around the same when there is no sheet material between 45 the upper and lower rolls.

Fig. 4 shows a modified arrangement of rolls wherein the lower roll 20 is provided with a comparatively wide groove 21 which is adapted to apply the adhesive tape to comparatively 50 wide folded-over marginal portions of the upper sheets and to press the edges of the tape firmly against these portions as well as against the adjoining body portions of the sheets, as shown.

Figs. 6 and 7 illustrate an optional form of 55 guide means which is more particularly suitable for use with leather upper sheets that are ordinarily characterized by having much narrower marginal portions adjoining the back seam than is common with the satin or similar upper elements. The guide member 140 shown in Fig. 6 may have a lower portion 60 with a slot 141 similar to the guide slot 41 of member 40 described above. The up- 65 standing portion of member 140, however, is

formed of sheet metal with a central groove 142 designed to receive the leather seam and with curved portions 143 designed to permit the movement of the leather over the same with the minimum of friction, the curved 70 portions and groove merging into a substantially flat curved surface adjoining the juxtaposed rolls. This guide means may be provided with suitable sight openings 148^a and with a notch similar to notch 49.

Figs. 9 and 10 illustrate another type of 75 guide member particularly suitable for use with leather upper portions, this member comprising a tape-guiding slot 241 with a small metal block 242 thereabove having a shallow central groove 243 designed to receive the leather seam and to center the same 80 in relation to the rolls.

It is obvious that a machine of this character is adapted to receive sheet units or the like 85 which are formed to have a concavo-convex shape and to turn the same, applying reinforcing tape to the seam as turned so that the tape and sheet material are united when in the relative positions they will permanently occupy 90 in the shoe, the use of rolls for this purpose permitting continuous smooth application of the tape and avoiding the puckering or pulling of the same. In this connection it may

be noted that the diameters of the rolls 10 and 20 may be suitably proportioned to vary the 95 peripheral speeds of the rolls 10 and 20. Thus, for example, in applying tape to back 100 seams I have found it advantageous to drive the upper roll at a slightly higher peripheral speed than the lower roll. While the guide means shown in Figs. 6 and 7, and 8 and 9 are particularly suitable for use with leather, the guide means shown in Figs. 1, 2, 3, etc. 105 may also be used with leather back seams, the particular guide means used depending upon the class of work and the individual preference of the operator in many cases. The notches 49 and 149 in the guide means 110 are particularly desirable for use with leather upper sheets, since they eliminate any tendency of the leather ridge formed by the back seam to catch upon the inner edge of the guide.

I claim:

1. In a machine of the class described, a pair of rolls for applying adhesively coated tape to a sheet unit, one of said rolls having a convexly curved peripheral face, the other roll having a concavely curved peripheral face, means for guiding tape between juxtaposed portions of the rolls, and a guiding element arranged to direct a seamed sheet unit between the rolls, said element having a ridge to engage marginal portions of the element adjoining the seam, said guide element being juxtaposed to the roll with the concavely curved face.

2. In a machine of the class described, a pair of rolls for applying adhesively

coated tape to a sheet unit, one of said rolls having a convexly curved peripheral face, the other roll having a concavely curved peripheral face, and means for guiding tape between juxtaposed portions of the rolls, a guiding element curved in the general direction of the second-named roll and being arranged to direct a seamed sheet unit between the rolls, and a spreading member between the guiding element and the second-named roll and arranged to spread sheet portions of the unit.

3. In a machine of the class described, a pair of rolls for applying adhesively coated tape to a sheet unit, one of said rolls having a convexly curved peripheral face, the other roll having a complementarily curved peripheral face, means for guiding tape between juxtaposed portions of the roll, and a guiding element having a general curvature in the direction of the periphery of the second-named roll and being arranged to direct a seamed sheet unit between the rolls, said guiding element comprising a rib having a pointed outer end to engage marginal portions of the unit adjoining the seam.

4. In a machine of the class described, a pair of rolls for applying adhesively coated tape to a sheet unit, one of said rolls having a convexly curved peripheral face, the other roll having a complementarily curved peripheral face, and means for guiding tape between juxtaposed portions of the rolls, a guiding element arranged to direct a seamed sheet unit between the rolls, said element having a ridge to engage marginal portions of the element adjoining the seam, said ridge decreasing in height at the end adjoining the rolls, and sight openings at either side of the ridge.

5. In a machine of the class described, a pair of rolls for applying adhesively coated tape to a sheet unit, one of said rolls having a convexly curved peripheral face, the other roll having a complementarily curved peripheral face, means for guiding tape between juxtaposed portions of the rolls, a guiding element arranged to direct a seamed sheet unit between the rolls, a spreading member adjoining the guiding element and arranged to spread sheet portions of the unit apart, and elements disposed at either side of the rolls to engage sheet portions which extend laterally from the rolls.

6. In a machine of the class described, a pair of juxtaposed rolls, means for supplying tape between the rolls, and guide means for sheets which are stitched substantially face to face, said guide means being adapted to spread apart the sheets adjoining the seam whereby they tend to extend in opposite directions respectively from the seam as they pass between the rolls, and means adapted to spread marginal portions of the sheets which

project beyond the seam back toward the body portions of the sheets.

7. In a machine of the class described, a pair of juxtaposed rolls, means for supplying tape between the rolls, and guide means for sheets which have been stitched substantially face to face and are being fed to the rolls, said guide means being adapted to spread apart the sheets adjoining the seam whereby they tend to extend in opposite directions respectively from the seam as they pass between the rolls, and other means adapted to spread marginal portions of the sheets which project beyond the seam back toward the body portions of the sheets, said means including a tapered ridge inclined downwardly toward the portions of the rolls which adjoin each other.

8. In a machine of the class described, a pair of juxtaposed rolls, means for supplying tape between the rolls, and means to receive units comprising sheets which are stitched substantially face to face, said means being adapted to spread apart the sheets adjoining the seam whereby they tend to extend in opposite directions respectively from the seam as they pass between the rolls, and guide means adapted to engage marginal portions of the sheets which adjoin the seam back toward the body portions of the sheets, said means including a tapered ridge member inclined downwardly toward the portions of the rolls which adjoin each other, and sight openings at either side of said ridge, whereby the sheet units may be accurately fed to the rolls.

9. In a machine of the class described, a pair of juxtaposed rolls for applying adhesively coated tape to a sheet unit, means for directing tape to the bite of the rolls, a guide element to direct a seamed sheet unit between the rolls, said element having a ridge to engage marginal portions of the sheet element adjoining the bite of the rolls, a spreader disposed between the curved ridge and the adjoining roll, said spreader having a portion to engage the body portions of the sheets adjoining the seam as the sheet element passes into the bite of the rolls.

10. In a machine of the class described, a pair of juxtaposed rolls for applying adhesively coated tape to a sheet unit, means for directing tape to the bite of the rolls, a guide element to direct a seamed sheet unit between the rolls, said element having a ridge to engage marginal portions of the sheet element adjoining the seam, the apex portion of said ridge adjoining one of the juxtaposed rolls and having a general curvature in the direction of the curvature of the periphery of the roll, said ridge decreasing in height at the end adjoining the bite of the rolls, a spreader disposed between the curved ridge and the adjoining roll, said spreader having a portion to engage the body portions of the sheets adjoining the seam as the sheet element passes into the bite of the rolls.

- said one of the rolls, said ridge merging into a substantially flat surface of the guide element adjoining the bite of the rolls, and a spreader adapted to engage the body portions of the sheets adjoining their seam, said spreader being disposed between said substantially flat portion of the guide element and the adjoining roll. 70
11. In a machine of the class described, a pair of juxtaposed rolls for applying adhesively coated tape to a sheet unit, means for directing tape to the bite of the rolls, a guide element to direct a seamed sheet unit between the rolls, said element having a ridge to engage marginal portions of the sheet element adjoining the seam, the apex portion of said ridge being disposed adjoining one of the juxtaposed rolls, said ridge merging into a substantially flat surface of the guide element adjoining the bite of the rolls, a spreader adapted to engage the body portions of the sheets adjoining their seam, said spreader being disposed between said substantially flat portion of the guide element and the adjoining roll, and elements disposed at either side of the juxtaposed portions of the roll and adapted to engage the body portions of the sheets in order to assist the turning of the sheet unit as it passes between the rolls. 75
12. In a machine of the class described, a pair of juxtaposed rolls for applying adhesively coated tape to a sheet unit, means for directing tape to the bite of the rolls, a guide element to direct a seamed sheet unit between the rolls, said element having a ridge to engage marginal portions of the sheet element adjoining the seam, the apex portion of said ridge adjoining one of the juxtaposed rolls and having a general curvature in the direction of the curvature of the periphery of said one of the rolls, said ridge decreasing in height at the end adjoining the bight of the rolls and merging into a substantially flat surface of the guide element adjoining the bight of the rolls, and elements disposed at either side of the juxtaposed portions of the rolls to aid in the turning of a sheet unit passing between the latter. 80
13. In a machine of the class described, a pair of juxtaposed rolls for applying adhesively coated tape to a sheet unit, means for directing tape to the bite of the rolls, a guide element to direct a seamed sheet unit between the rolls, said element having a ridge to engage marginal portions of the sheet element adjoining the seam, the apex portion of said ridge being disposed adjoining one of the juxtaposed rolls, said ridge decreasing in height at the end adjoining the bight of the rolls and merging into a substantially flat surface of the guide element adjoining the bite of the rolls, and a spreader adapted to engage the body portions of the sheets adjoining their seam, said spreader being disposed between said substantially flat portion of the 85
- guide element and the adjoining roll, said ridge portion having a pointed outer edge that is adapted to engage between marginal portions of a sheet unit which are disposed substantially face to face. 90
14. A machine of the class described comprising a pair of superimposed rolls, a combined guide unit for a sheet member and for a run of adhesively coated tape, said guide element having a channel directed toward the bite of the rolls and dimensioned to direct a tape to the same, said channel being inclined upwardly toward the bite of the rolls, said guide element also providing a ridge inclined downwardly toward the bite of the rolls, said ridge being adapted to engage the marginal portions of a sheet unit adjoining the seam of the same. 95
15. A machine of the class described comprising a pair of superimposed rolls, a guide element adjoining the bite of the rolls, said guide element having an upwardly directed channel to receive a ribbon from the lower portion of the periphery of the lower roll and to direct the same to the bite of the rolls, said guide element also providing a guideway which is inclined toward the channel in the direction of the bite of the rolls, whereby the tape and a seamed sheet unit may be brought into juxtaposition as they pass between the rolls. 100
16. A machine of the class described comprising a pair of substantially parallel shafts, a roll mounted on each shaft, said rolls being juxtaposed, a tape guide adjoining one of the rolls and being arranged to supply tape to the bite of the rolls, common drive means for said shafts effecting the rotation of the shafts at speeds which have a predetermined ratio to each other, the ratio of the diameter of the roll remote from the guide to the diameter of the roll adjoining the guide being somewhat greater than the ratio of the speeds of the corresponding shafts, whereby the roll remote from the guide has a peripheral speed slightly greater than that of the other roll. 105
